GAME APPARATUS

William Harold Huenergardt, Chicago, Ill., assignor to Rock-Ola-Manufacturing Co., Chicago, Ill., a corporation of Illinois

Application February 16, 1935, Serial No. 6,799

13 Claims. (Cl. 273—121)

This invention relates to a game apparatus.

It is an object of this invention to provide an improved game apparatus which is relatively simple and inexpensive in construction and efficient in use.

Another object of the present invention is to provide a game apparatus comprising the combination of: a cabinet including a member providing a ball-playing surface having at least two ball exit openings formed therein; an endless ball conveyor having a run movable transversely across the said playing surface above the latter and having a run movable transversely of the said playing surface below the same; a runway 10 upon said playing surface adapted to conduct balls one at a time onto the upper run of said conveyor; means including a device actuated by a ball passing through one of said exit openings to move said ball conveyor in a step by step motion 15 so as to transport a ball carried thereby from one point to another thereby relative to and across said playing surface; and means including a device actuated by a ball entering the other of said exit openings for elevating the same into 20 said runway.

A further object of the invention is to construct the new apparatus in such a manner that the ball-elevating means referred to in the preceding paragraph is controlled and energized by 30 means of the elevating device which elevates the spent balls from a point below the playing surface up onto the latter and in front of the ball-propelling device or player.

Other objects will appear hereinafter.

35 The invention consists in the novel combination and arrangement of parts to be hereinafter described and claimed.

The invention will best be understood by reference to the accompanying drawings, showing 40 the preferred form of construction and in which:

Fig. 1 is a fragmentary perspective view, partly in section, of a preferred form of the new game apparatus;

Fig. 2 is an elevational detail view;

45 Fig. 3 is a sectional detail view;

Fig. 4 is a sectional view on line 4—4 in Fig. 1;

Fig. 5 is a fragmentary bottom plan view;

50 Fig. 6 is a top plan view of the new game apparatus;

Fig. 7 is a sectional view on line 7—7 in Fig. 6; and

Fig. 8 is a sectional view on line 8—8 in Fig. 3.

55 A preferred form of the new game apparatus

is shown in the drawings, is therein generally indicated at 16, and comprises a cabinet 11 which includes an inclined playing board 12 having spaced groups of ball exit openings 13 and 29 therein. Arranged in the cabinet 11 at one side of the playing surface 12 is a ramp 14 and arranged at the lower end of the ramp 14 is a ball-propelling device or plunger 15 by means of which balls may be propelled, one at a time, up the ramp 14 onto the inclined playing board 12 so that they may gravitate over the latter and enter into one of the ball exit openings 13 or 29.

The present game apparatus comprises a series of inclined runways 16 which are arranged in 15 the cabinet 11 below the inclined playing board 12 and each of which has communication at its upper end with one of the exit openings 13 or 29 (Fig. 1); these runways 16 opening at their lower ends, as at 17, (Fig. 1) into a housing 18 20 which is arranged in the cabinet 11 below the inclined playing board 12.

Rotatably journaled in the housing 18, upon a shaft 21, is a disc or gravity motor 19 which is provided with an annular row of ball-receiving 25 pockets 20 which are arranged at intervals radially around its peripheral surface.

Carried by the shaft 21 which supports the disc or motor 19—20 is a gear 22 (Figs. 1 and 3) and this gear 21—22 meshes with a gear 23 30 which is carried by a horizontal shaft 24 which is suitably journalled in the cabinet 11 below the inclined playing board 12.

Carried by the shaft 24 adjacent one end thereof is a sprocket 25 which meshes with the 35 lower run 26 of an endless ball conveyor or chain 27 which is guided in the cabinet 11 by suitable guiding means in the form of rollers 94; this arrangement of the endless conveyor 27 being such that the upper run 28 thereof works 40 above the inclined playing board 12 while the lower run 26 thereof works below the inclined playing board 12 (Fig. 1).

When a played or spent ball enters into and passes through one of the ball exit openings 13 45 it travels down the corresponding runway 16 (Figs. 1 and 3) and enters, by way of the corresponding inlet 17, into the housing 18, wherein it is deposited in one of the ball-receiving pockets 20 of the disc or motor 19, whereupon the disc 19 50 is rotated, under the weight of a ball arranged thereon (counterclockwise, Fig. 1). This movement of the disc 19 advances the upper run 28 of the endless ball conveyor 27 and the playing ball 30 carried thereby (left to right, Fig. 1). 55

- On the other hand, if a played ball enters one of the ball exit openings 29 it will, upon passing down the corresponding runway 16, into the housing 18 and into a corresponding one of the ball-receiving pockets 20 in the disc 19, rotate the disc 19 (clockwise, Fig. 1) and thereby advance the upper run 28 of the endless ball conveyor 27 and the ball 30 carried thereby (right to left, Fig. 1).
- After a played ball has completed its movement of the disc or gravity motor 19 and the endless ball conveyor 27 it engages a stop 31 which is arranged in the housing 18, adjacent the bottom of the disc 19, and when the ball engages this stop 31 it stops the operation of the disc 19 and chain 27; the ball being then discharged by the corresponding stop 31 out of the housing 18 through the corresponding outlet 32 formed in the latter and into the corresponding inclined runway 33 by which it is conducted to a point adjacent the ball-elevating device 34, by means of which it may again be elevated up into the ramp 14 in front of the propelling device or plunger 15.
- Provided upon and slightly above the inclined playing board 12 (Figs. 1 and 3) is an inclined ball runway 35 and arranged adjacent the upper end of this runway 35 is the mouth or outlet 36—35 of a ball elevating tube or guideway 37 through which a playing ball is automatically elevated up to the level of the playing surface 12 and into the inclined runway 35 by means, and in a manner, presently to be described.
- When the endless conveyor or chain 27 is operated so that its upper run 28 moves from left to right (Fig. 1), the ball 30 carried upon the upper run 28 thereof engages a ball deflector 95 (Fig. 1) by means of which the ball 30 is deflected off the upper run 28 of the chain 27 onto the inclined playing board 12 so that it may gravitate into either one of two ball exit openings 38 which are provided in the inclined playing board 12 (Fig. 1) adjacent the lower end thereof.
- Associated with the exit openings 38 is a score-indicating or registering device in the form of a dial 39 which is mounted below the inclined playing board 12, upon a horizontal shaft 40, the face of the dial 40 being visible through a sight opening 41 which is provided in the inclined playing board 12 (Fig. 1).
- Also carried by the shaft 40, adjacent the opposite end thereof from the dial 39, is a score-indicating or registering dial 42 and mounted upon the shaft 40 is a U-shaped fork or member 43 which includes spaced arms 44 which are arranged on opposite sides of the dial 42. This yoke or member 43—44 has a pair of spaced extensions 45 which are arranged above the open upper ends or mouths of vertical ball chutes 46 (Fig. 1); these chutes 46 being arranged below, and in communication with, ball exit openings 38 (Fig. 5) and similar chutes 48 being arranged below and in communication with the exit openings 38. A member 89, which is similar to the member 43—44 is mounted upon the shaft 40 in association with the dial 39 (Fig. 5) and this member has extensions 47 which are arranged under the exit openings 38.
- A ball deflector 81, similar to the deflector 95 is arranged upon the inclined playing board 12 adjacent the opposite end of the upper run 28 of the chain 27 so that when the upper run 28 of the chain 27 is moved (right to left Fig. 1) the ball 30 carried thereby will be swept off the

chain 23 onto the inclined playing board 12 so that it gravitates into one of the exit openings 38 arranged above the vertical ball chutes 46.

The vertical ball chutes 46 open into a common inclined chute or runway 49 and the vertical ball chutes 48 open into a common inclined chute or runway 50 (Fig. 1). These chutes or runways 49 and 50 open at their lower ends into the lower end portion of the ball elevator guideway or chute 37.

Mounted in the cabinet 11 below the inclined playing board 12 is a horizontal shaft 51 and carried by this shaft 51 adjacent one end thereof is a ball elevating arm 52. This arm 52 has an extension 53 which projects into the ball elevator guideway 37 through a slot 54 formed in the wall of the guideway 37.

Pivottally mounted adjacent the bottom of the ball elevator guideway 37 is a latch member 55 which is urged into latching engagement with the ball seat or extension 53 of the elevator 52 by means of a spring 56.

The shaft 51 has a crank arm 57 at one end thereof (Figs. 2 and 5) and having one attached to this crank arm 57 so as to urge the latter and the shaft 51 (in a counterclockwise direction, Fig. 2) is a spring 58.

Attached to the crank arm 57 of the shaft 51 is a slide bar 59 which has a pin and slot connection 60 with a slide bar 61 which controls the operation of the elevating device 34, in a manner to be described presently.

Carried by the slide bar 61 is a roller or cam 62 and this roller or cam 62 is engageable with an arm 63 of a member 64 which is pivotally mounted between its ends upon a pintle or shaft 65 which is arranged in the cabinet 11 below the inclined playing surface 12. Attached to the slide bar 61 is a resetting spring 66.

Likewise mounted upon the shaft 65 adjacent the member 64 is a member 66 which includes oppositely extending arms 67 and 68, the arm 67 of the member 66 being attached to the arm 69 of the elevator operating handle 70. Likewise attached to the arm 67 of the member 66 so as to urge the latter in a clockwise direction, Fig. 2, is a spring 71, and interconnecting the arms 63 and 68 is a spring 72 (Fig. 2).

The ball elevating device 34 includes a guideway 89 (Fig. 2) and working in this guideway 89 is an arm or ball seat portion 90 of an elevator member 91 which is pivotally mounted in the cabinet 11, below the inclined playing board 12, as at 92 (Fig. 2). The elevator member 91 is pivotally connected to the slide bar 59, as at 93 (Fig. 2).

Pivottally mounted upon the inclined playing board 12, under the upper run 28 of the chain 26—27—28, is a ball trough 73 which is normally urged, by spring 75, (in a clockwise direction, from dotted to full lines, Fig. 4). Engageable with the bottom wall 76 of this trough 73 is an upright arm 77 which is carried by a slide bar 78 which is slidably mounted upon the inclined playing board 12 below the latter; this arm 77 extending through and working in a vertical slot 79 which is formed in the inclined playing board 12 (Fig. 4). The coin slide 80 is pivotally connected to the slide bar 78 by means of a link 96 (Fig. 5).

Operation

The present game apparatus is preferably played with two balls, one of which is arranged, at the start of play, upon the upper run 28.

of the chain 26 and upon the ball seat 13 at the lower end of the runway 35. The other of the two balls is elevated into the ramp 14, in front of the player 15, by operation of the elevator operating slide rod 69-70, whereupon it may be propelled onto the upper portion of the inclined playing board 12 so that it may gravitate thereover and enter into one of the ball exit openings 13 or into one of the ball exit

10 openings 29 (Fig. 1).

If the played ball enters into one of the ball exit openings 13 it travels down the corresponding runway 16 and through the corresponding opening 17 into the housing 18 wherein it engages in one of the ball pockets 20 which are provided in the disc or ball-operated gravity motor 19, thereby rotating the disc 19 (in a counterclockwise direction, as seen looking from right to left, Fig. 1). This movement of the disc or motor 19 acts through the gears 22-23, shaft 24 and sprocket 25 to move the endless ball-conveyor or chain 27 in such a manner that the upper run 28 thereof travels from (left to right, as seen looking from right to left, Fig. 1), whereupon the ball 39 carried by the chain 26 will engage the deflector 85 and be swept thereby off the upper run 28 of the chain 27. The ball thus swept off the chain 27 will thereupon gravitate over the inclined playing board 12 into one of the ball exit openings 38, it being noted that the movement of the disc 19 and of the chain 27 is stopped by the engagement of the ball carried in one of the pockets 20 of the disc 19 with the corresponding ball stop 31 by which the ball is deflected into the corresponding one of the inclined runways 33 (Fig. 1), by which it is conducted to a point adjacent the elevating device 34.

Similarly, a ball entering one of the ball exit openings 29 will travel down a corresponding one of the runways 16, through the corresponding inlet 17, into the housing 18 and into one of the pockets 20 in the disc 19, whereupon the disc 19 will be operated (in a clockwise direction, Fig. 1). This movement of the disc 19, acting through the gears 23-22, shaft 24 and sprocket 25 will operate the chain 27 so to move the upper run 28 of the chain 27 (right to left as seen looking from right to left, Fig. 1), thereby moving the ball 39 into engagement with the deflector 81. The ball 39 will thus be swept off the chain 26-27-28 and will gravitate over the playing surface 12 into one of the ball exit openings 32.

As a played ball passes into one of the exit openings 32 it engages the corresponding arm 48 of the member 43, thereby rocking the latter and the shaft 49 (counterclockwise, as seen in Fig. 1) so as to advance the dial 42.

Similarly, a played ball passing through one of the exit openings 38 will engage the corresponding arms 47 of the member 83, thereby rocking the member 83 and the shaft 60 (counterclockwise, as seen in Fig. 1) so as to advance the dial 39 relative to and past the sight opening 41 which is provided in the playing surface 12.

A played ball passing through one of the exit openings 38 or 32 into the corresponding chute 48-50 or 46-49 passes down the latter into the ball elevator guideway or chute 37 wherein it engages the latch member 55. This engagement of the ball with the latch member 55 urges the latter (counterclockwise, Fig. 3) against the action of the spring 56, thereby releasing the

latch member 55 from latching engagement with the arm or ball seat portion 53 of the ball elevator 52-53. The tensioned spring 58 then acts through the crank arm 57 to rock the shaft 51 and the ball elevator 52-53 (counterclockwise, Figs. 2 and 3, from full to dotted line position, Fig. 3), thereby automatically elevating the ball up the guideway 37 into the runway 35, into which the thus elevated ball is directed by the hood 85 which is formed on the 10 guideway 37 above the mouth or outlet 36 thereof (Fig. 3); it being noted that the crank 57 pivots upon the shaft 51 during the foregoing movement (counterclockwise, Fig. 3), thereby moving the crank 57, shaft 51, and slide rod 59 from 15 full to dotted line position (Fig. 2).

The ball elevator member 52-53 remains in raised position (as in dotted lines, Fig. 3) until it is reset back into its initial position (as in full lines, Fig. 3), which is accomplished through the 20 operation of the ball elevating device 34 and its operating rod 69-70.

In order to operate the ball-elevating device 34 the slide rod 70-69 is pushed inwardly (left to right, Fig. 2), thereby pivoting the member 66 25 (counterclockwise, from full to dotted line position, Fig. 2). This movement of the member 66 acts, through the spring 72, to pivot the member 64 (counterclockwise, from full to dotted line position, Fig. 2). This movement of the member 64 causes the arm 63 thereof to engage the cam or roller 62, thereby shifting the slide rod 61 (right to left, Figs. 2 and 5). This movement of the slide rod 61 acts through the pin and slot connection 60 of the same with the slide rod 58 35 to shift the latter (right to left, Figs. 2 and 5) and this movement of the slide rod 59 in turn acts through the crank arm 57 of the shaft 51 to rock the latter (clockwise, from dotted to full-line position, Fig. 2) and the ball elevator 40 member 52-53 reengages the arm 53 thereof with the latch member 55 and at the same time tensions the energy storing device or spring 58 so that the ball elevator 52-53 may again be operated as soon as another ball passes into the 45 guideway 37 and engages the latch 55.

After the foregoing movement (right to left, Fig. 2) the slide rod 61 is returned or reset into its initial position (left to right, Fig. 2) by operation of the resetting spring 97, but the slide 50 rod 59 and crank 57 are latched in full line position, (Fig. 2), against the action of the spring 58, by the latching engagement of the arm 53 with the latch member 55, (Fig. 3).

Likewise, the foregoing movement of the slide 55 rod 61 (right to left, Fig. 2) acts through the pivotal connection 93 to pivot the ball elevator member 90-91 (clockwise from full to dotted line position, Fig. 2) and during this movement the end portion or ball seat 80 of the elevator 60 works through the guideway 89 so as to elevate a ball up into the ramp 14 in front of the propelling device or plunger 15.

If the ball 30 is disposed upon the upper run 28 of the chain 27 at the end of a game the same 65 may be dislodged therefrom, and returned to the runway 35, by operation of the coin slide 80 as follows:

When the coin slide 80 is pushed inwardly (left to right, Fig. 1, right to left, Fig. 5) it acts 70 upon the pivoted link 95 to pivot the latter (clockwise from full to dotted line position Fig. 5) and this movement of the member 95 in turn acts upon the slide bar 78 to move the latter (left to right, Fig. 5, right to left, Fig. 4) and 75

this movement of the slide bar 78, in turn, acts upon the upright arm 79 thereof to move the latter (from full to dotted line position, Fig. 4) whereupon the arm 77 engages the trough 76-73 5 and pivots the latter (counterclockwise, from full to dotted line position, Fig. 4) thereby discharging the ball 39 out of the trough 73-76 onto the inclined playing board 12. The ball 39 thus discharged from the trough 73 onto the 10 inclined playing board 12 is guided along the latter by the rail 86 into the ball exit opening 87 (Figs. 1 and 3), whence it falls into a chute 88, and is in turn conducted by the latter into the ball elevator guideway 37 wherein it engages the latch 55 and releases the latter and 15 is, thereupon, elevated by the ball elevator 52-53 up the guideway 37 onto the runway 35 by which it is delivered onto the upper run 28 of the chain 27 into position for play to be resumed.

While I have illustrated and described the preferred form of construction for carrying my invention into effect, this is capable of variation and modification, without departing from the 25 spirit of the invention. I, therefore, do not wish to be limited to the precise details of construction set forth, but desire to avail myself of such variations and modifications as come within the scope of the appended claims.

30 I claim:—

1. In a game apparatus, the combination of: a cabinet including a member providing a playing surface and said member having a ball exit opening or pocket therein; means for propelling a ball over said playing surface so that it may enter into said ball exit opening or pocket; an endless ball conveyor in said cabinet for transporting a ball from one point to another relative to and across said playing surface; and means including a device actuated by a ball entering said ball exit opening or pocket for operating said endless ball conveyor.

2. In a game apparatus, the combination of: a cabinet including a member providing a playing surface and said member having two spaced ball exit openings therein; means for propelling a ball over said playing surface so that it may enter into one of said exit openings; an endless ball conveyor in said cabinet for conveying or transporting a ball from one point to another relative to and across said playing surface; a runway upon said playing surface for conducting a ball onto said conveyor; means including a device actuated by a ball entering one of said exit openings for operating said conveyor; and means including a device actuated by a ball entering the other one of said exit openings for elevating a ball from a point below said playing surface up onto the latter and into said runway.

3. In a game apparatus, the combination of: a cabinet including a member providing a playing surface and said member having two spaced ball exit openings therein; means for propelling a ball over said playing surface so that it may enter into one of said exit openings; an endless ball conveyor in said cabinet for conveying or transporting a ball from one point to another upon said playing surface; a runway upon said playing surface for conducting a ball onto said conveyor; means including a device actuated by a ball entering one of said exit openings for operating said conveyor; means including a device actuated by a ball entering the other one of said exit openings for elevating a ball from a point below said playing surface up onto the

latter and into said runway; and means for deflecting a ball off from said conveyor onto said playing surface so that it may gravitate into the said other one of said ball exit openings.

4. In a game apparatus, the combination of: 5 a cabinet including a member providing a playing surface having a ball exit opening therein; means including an energy-storing device released by a ball passed through said exit opening to a point below said playing surface for automatically elevating a ball from a point below said playing surface up to the level of the same; means for propelling a ball onto said playing surface so that it may enter into said ball exit opening; means for elevating a ball 10 from a point below said playing surface up to the level of the same and in front of said propelling means; and means coacting with said third-named and elevating means for energizing said energy storing device. 20

5. In a game apparatus, the combination of: a cabinet including a member providing a ball-playing surface provided with a ball-receiving pocket, an endless article-conveyor in said cabinet for conveying or transporting an article 25 from one point to another relative to and across said playing surface; and means including a device actuated by a ball entering said ball-receiving pocket for moving said conveyor relative to and across said playing surface. 30

6. In a game apparatus, the combination of: a cabinet including a member providing a playing surface having two spaced ball exit openings therein; means for propelling a ball over said playing surface so that it may enter into either one of said exit openings; a ball conveyor in said cabinet for conveying or transporting a ball from one point to another relative to and across said playing surface; and means including a device actuated by a ball entering one of said exit openings for moving said conveyor in one direction relative to and across said playing surface; said second-named and last-mentioned means including a device for moving said conveyor in a direction opposite to the said first-named direction if and when a ball enters the other of said exit openings. 45

7. In a game apparatus, the combination of: a cabinet including a member providing a playing surface having two spaced ball exit openings therein; an endless ball conveyor in said cabinet for conveying or transporting a ball from one point to another relative to and across said playing surface; a runway upon said playing surface for conducting a ball onto said conveyor; means including a device actuated by a ball entering one of said exit openings for moving said endless conveyor so as to transport or convey a ball thereby from one point to another relative to and across said playing surface; and means including a device actuated by a ball entering the other of said exit openings for automatically elevating a ball from a point below said playing surface up into said runway so that it may travel along the latter 60 onto said conveyor.

8. In a game apparatus, the combination of: a cabinet including a member providing a playing surface having two spaced ball exit openings therein; a ball conveyor in said cabinet 70 for conveying or transporting a ball from one point to another relative to and across said playing surface; a runway upon said playing surface for conducting a ball onto said conveyor; means including a device actuated by a 75

- ball entering one of said exit openings for moving said conveyor so as to transport or convey a ball thereby from one point to another relative to and across said playing surface; and 5 means including a device actuated by a ball entering the other of said exit openings for automatically elevating a ball from a point below said playing surface up into said runway so that it travels along the latter onto said 10 conveyor.
9. In a game apparatus, the combination of: a cabinet including a member providing a playing surface having two spaced ball exit openings therein; an endless ball conveyor in said cabinet for conveying or transporting a ball from one point to another relative to and across said playing surface; a runway upon said playing surface for conducting a ball onto said conveyor; means including a device actuated by a ball entering one of said exit openings for moving said endless conveyor so as to transport or convey a ball thereby from one point to another relative to and across said playing surface; means including an energy-storing device 15 released by a ball entering the other of said exit openings for automatically elevating a ball from a point below said playing surface up into said runway so that it may travel along the latter onto said conveyor; means for propelling a ball onto said playing surface so that it may enter into the said first-named one of said exit openings; means for elevating a ball from a point below said playing surface up to the level of the same and in front of said propelling means; and means coacting with said fourth-named and elevating means for energizing said energy-storing device. 20
10. In a game apparatus, the combination of: a cabinet including a member providing a playing surface having two spaced ball exit openings therein; an endless ball conveyor in said cabinet for conveying a ball from one point to another relative to and across said playing surface; means including a device actuated by a ball entering one of said exit openings for operating said conveyor; an operating mechanism in said cabinet actuated by a ball entering the other of said exit openings; and means for deflecting a ball from said conveyor into the said other one of said exit openings so that it may actuate 25 said operating mechanism.
11. In a game apparatus, the combination of: a cabinet including a member providing a playing surface having three ball exit openings 30
- therein; an endless ball conveyor in said cabinet for conveying a ball from one point to another relative to and across said playing surface; means including a device actuated by a ball entering one of said exit openings for operating said conveyor; an operating mechanism in said cabinet actuated by a ball entering one of the other two of said exit openings; means for deflecting a ball from said conveyor into the said one of said exit openings so that it may actuate 35 said operating mechanism; and means actuated by a ball entering the remaining one of said exit openings for automatically elevating a ball from a point below said playing surface up onto said conveyor. 40
12. In a game apparatus, the combination of: a cabinet including a member providing a playing surface having ball exit openings or pockets therein; an endless conveyor in said cabinet for transporting a ball from one point to another relative to and across said playing surface; means including a device actuated by a ball entering one of said exit openings or pockets for operating said conveyor; and means including a device actuated by a ball entering the other of said exit openings or pockets for automatically elevating a ball from a point below 45 said playing surface up onto said conveyor.
13. In a game apparatus, the combination of: a cabinet including a member providing a playing surface having two spaced ball exit openings therein; an endless ball conveyor in said cabinet for conveying or transporting a ball from one point to another relative to and across said playing surface; a runway upon said playing surface for conducting a ball onto said conveyor; means including a device actuated by a ball entering one of said exit openings for moving said endless conveyor so as to transport or convey a ball thereby from one point to another relative to and across said playing surface; means including a device actuated by a ball entering the other of said exit openings for automatically elevating a ball from a point below said playing surface up into said runway so that it may travel along the latter onto said conveyor; means for propelling a ball onto said playing surface so that it may enter into the said first-named one of said exit openings; and means for elevating a ball from a point below 50 said playing surface up to level of the same and in front of said propelling means. 55

WILLIAM HAROLD HUENERGARDT.
